UNITED STATES PATENT OFFICE

CONRAD OSIUS, OF STETTIN, GERMANY

HOLDING MEANS FOR GLASS

Application filed August 16, 1929, Serial No. 386,367, and in Germany December 8, 1927.

This invention relates to a means for holding sheets of glass in iron window frames.

A primary object of the invention is the provision of a novel means which will firmly hold the glass in the frame, this holding action being of such nature that while the glass is pressed firmly against the frame there is no tendency for the same to splinter or chip at the edges.

10 A further object is to furnish a holding means of the kind in question which is capable of ready application and is, therefore, very inexpensive in use.

Other objects and advantages of the invention will become obvious as the description proceeds.

It has hitherto been usual to secure sheets of glass in iron window frames by means of pins or the like. These pins are inserted into 20 holes which are drilled in the cross bars of the frame, and are of such length that they project laterally beyond the cross bars, these projecting portions thrusting against the glass. If the holes in the cross bars are positioned in such manner that the pins thrust 25 relatively strongly against the glass, there is a certain danger of the glass chipping at the edges or even becoming broken entirely when the pins are inserted into position. If 30 on the other hand the holes are somewhat further away from the glass, so that the latter is held merely loosely by the pins, the glass is capable of a certain movement in the frame and is also liable to become broken 35 upon the application of a strong pressure.

The drilling of the holes in the cross-bars of the frame is not only a lengthy matter but is not always simple to perform, at least with the proper degree of accuracy, so that 40 accordingly the mounting of a sheet of glass with the assistance of the pins hitherto in use is both tedious and expensive, as at least four borings are necessary for each sheet or pane, and as a matter of fact it is usual to provide eight borings if the sheet or pane is to be securely held at all four edges.

According to the invention these disadvantages are overcome by the use of a fastening means which renders the drilling of the cross bars entirely unnecessary, and enables

the sheets of glass to be secured in position in rapid and secure manner. When the glass is being secured in the frame it is quite within the choice of the workman to apply the fastening means in such manner that the glass is pressed with any desired degree of tightness against the frame.

According to the invention the fastening means in question consists of a resilient clip, which is placed over the bars of the window frame, and possesses lateral projections thrusting against the glass. The clips by reason of the spring pressure are pressed in such fashion against the two sides of the bars that the same are firmly held by friction.

The clips are assisted in their hold on the bars by reason of the fact that teeth or serrations are furnished on the arms of the clips, these teeth or serrations being pressed by the resiliency of the clips against the surface of the bar.

The invention will now be described more fully with reference to the accompanying drawing, which shows two different embodiments by way of example.

Fig. 1 shows the clip in one form of embodiment when applied to a bar of the window frame, the bar itself being shown in section.

Fig. 2 is a view of the clip itself, Fig. 3 being a section along the line 3—3 in Fig. 1.

Fig. 4 is the perspective view of a modified form of embodiment of the clip,

Fig. 5 the clip according to Fig. 4 mounted in position on a window bar, which is shown in section,

Fig. 6 a top view of the clip according to Fig. 4, and

Fig. 7 the part of a window frame in plan.

Referring now to the drawing, the holding means consists of a U-shaped clip *a*, which is stamped out from resilient sheet steel or steel band. The clip itself may be of any desired width, although the preferred size will be one-third or one-half of an inch in length. In the embodiment according to Figs. 1—3 the arms of the clip are of equal length, while the distance between the same is equal to the thickness of a rail extended laterally from the window frame bar *b* at its thinnest point.

The ends *f* of the two arms are bent off laterally at *c* at right angles or at an obtuse angle, and are folded over in such manner that the edges *d* of these ends lie within the 5 clip, projecting inwardly to a slight extent beyond the straight vertical portions of the arms. The edges *d* are bevelled so as to form a knife edge.

If the sheets or panes of glass *e* are to be 10 mounted in the iron window frames *g*, the same are placed against the flange *h* of the frame bar *b* in the usual manner with or without a packing, in which connection it is possible to employ for each edge of the glass *e* 15 any desired number of clips. The clips are simply placed in the desired number over the rail of bar *b*. In securing the clips the ends of the arms are pressed somewhat apart, for which purpose it is possible to employ a pair 20 of pliers or any other suitable tool. The clip with the arms forced apart is placed over the rail of bar *b* until the points *i* of the lateral projections *f* enter into contact with the glass *e* and press against the same. When the clip 25 is placed in this manner over the bar rail, the knife edges *d* pass lightly over the sides of the bar rail in the direction of the glass, and immediately the tool holding the arms of the clip apart is removed the knife edges, by 30 reason of the resilient action, are pressed into the skin or the irregularities in the bar rail. When the tool is removed from the clip *a* the arms of the latter thrust against the rail of the window frame bar *b* at the upper end 35 thereof and are maintained in frictional contact with the bar by reason of the resiliency of the clip, so that in this manner and as a result of the gripping action of the knife edges *d* the clip *a* is held on the bar *b* in a 40 perfectly firm manner.

After the clip has been placed in position the clip is preferably given a light blow with a hammer, so that the same will firmly clamp the glass and also move over the rail bar *b* to the greatest possible extent. Each sheet of glass *e* may be held at each edge by means 45 of two or more clips, and each clip mounted on the bar rail of the window frame (Fig. 7) serves to hold the sheets of glass *e* situated on both sides of the bar rail.

In the embodiment according to Fig. 5 it is assumed that the rail of the window frame bar does not possess a conical form as shown 55 in Fig. 1, but that the lateral faces thereof are practically parallel to each other. It is possible on this type of bar to employ a clip constructed according to Fig. 2, or also to employ a clip in the embodiment according to 60 Fig. 4. In the same manner a clip according to Fig. 4 may also be employed in conjunction with a window frame bar having a rail of the form shown in Fig. 1.

In the embodiment of the clip according to 65 Figs. 4-6 the ends *f* of the arms of the clip

are also bent laterally at *c* at an obtuse angle. The ends, however, are not folded over in the manner of the previous embodiment. In order in this case to obtain sharp edges for engaging the bar rail, the clips are cut out from the sheet steel or steel band in such manner that the ends are bent laterally at *c* to form lugs *k*, which are somewhat broader than the arms of the clip *a*. The parts of the lugs *k* extending beyond the width of the arms are constructed to form tapered ears or teeth *m*, which are directed inwardly and when the clip is bent into U-shape project somewhat beyond the plane of the arms. These teeth *m* function exactly in the same manner as the bevelled edges *d* in the case of the embodiment according to Figs. 1-3.

The lugs *k* may be furnished with a U-shaped or other suitable incision, and the resulting tongue *n* bent upwardly approximately parallel with the arms, which will enable the clip to be readily grasped by the tool for the purpose of spreading the arms apart when fitting the clip in position.

In such cases in which glass is situated only on one side of the bar, for example edge panes, it is preferable to furnish only the one arm of the clip with a laterally projecting lug *k*, leaving the other arm straight so that the same will fit perfectly snugly against the outside of the bar.

What I claim as new and desire to secure by Letters Patent is:

1. Holding means for sheets of glass in iron window frames, comprising a U-shaped resilient clip engaged over a bar of the window frame and having laterally projecting lugs inclining toward the bar of the window frame with the opposite ends thereof impinging the bar and a sheet of glass positioned in the frame under the inherent tension of the material of the clip to secure the sheet of glass to the frame.

2. Holding means for sheets of glass in iron window frames, comprising a resilient clip engaged over a bar rail of the window frame and having laterally projecting lugs arranged at one end with tapered ears to impinge against the bar rail of the window frame and the opposite end to abut against a sheet of glass positioned in the frame.

3. Holding means for sheets of glass in iron window frames, comprising a resilient clip of U-shape engaged over a bar of the window frame and having at the free ends laterally projecting lugs arranged with one edge portion to engage and impinge the frame bar and the opposite edge to abut a sheet of glass positioned in the frame under the inherent tension of the clip.

4. Holding means for sheets of glass in iron window frames, comprising a resilient clip of U-shape engaged over a bar of the window frame, the arms of said clips having laterally projecting lugs turned inward and

the free ends thereof having knife edges to engage the bar of the window frame.

5. Holding means for sheets of glass in iron window frames, comprising a resilient ⁵ clip of U-shape engaged over a bar of the window frame, the arms of said clip having laterally projecting lugs folded over in an inward direction with the free ends engaging the bar of the frame and the folded portions ¹⁰ abutting a sheet of glass positioned in the frame to secure the glass in the frame under the inherent tension of the clip.

6. Holding means for sheets of glass in iron window frames, comprising a resilient ¹⁵ clip of U-shape engaged over a bar of the window frame, the arms of said clip having legs bent laterally from the arms at an angle greater than a right angle with the inner edges tapered to engage the bar of the window ²⁰ frame and portions of the leg engaging a sheet of glass positioned on the frame to secure the glass to the frame under the inherent tension of the clip.

7. Holding means for sheets of glass in ²⁵ window frames, comprising a resilient clip of U-shape engaged over a bar of the window frame, the arms of said clip having laterally projecting lugs wider than the arms arranged at the inner edge of the extended portions ³⁰ with tapered ears projecting beyond the inner faces of the arms of the clip to engage the bar of the window frame and the opposite free ends of the lugs adapted to abut a sheet of glass positioned in the frame under ³⁵ the inherent tension of the clip to secure the glass in the frame.

8. Holding means for sheets of glass in iron frames, comprising a resilient clip of U- ⁴⁰ shape engaged over a bar of the window frame, the arms of said clip having laterally projecting lugs with tapered ears extended inward from the lugs beyond the inner faces of the arms to engage the bar of the window frame, and tongues projecting laterally from ⁴⁵ said lugs for engagement by a tool to spread the arms of the clip to position the same over the bar of the window frame and the free ends of the lugs against a sheet of glass in the frame.

50. In testimony whereof I have affixed my signature.

CONRAD OSIUS.
